UNITED STATES PATENT OFFICE

156,877

SEPARABLE BASKET OR SIMILAR ARTICLE

Marie Fridinger, Vienna, Austria

Application May 18, 1948, Serial No. 146,428

Term of patent 3½ years

(Cl. D59—2)

To all whom it may concern:

Be it known that I, Marie Fridinger, a citizen of Austria, residing at 11 Arenbergring, Vienna III, Austria, have invented a new, original, and ornamental Design for a Separable Basket or Similar Article, of which the following is a specification, reference being had to the accompanying drawing, forming part thereof.

In the drawing

Fig. 1 is a perspective view of a separable basket or similar article showing my new design;

Fig. 2 is a top plan view of same; and

Fig. 3 is a bottom plan view of same.

I claim:

The ornamental design for a separable basket or similar article, substantially as shown.

MARIE FRIDINGER.
